(57) **CLAIM**

I claim the ornamental design for a headphone, as shown and described.

DESCRIPTION

This patent or application file contains at least one drawing executed in color. Copies of this patent or patent application

with color drawings will be provided by the Office by request and payment of the necessary fee.

FIG. 1 is a perspective view of a first embodiment of a headphone, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and

FIG. 8 is a rear, perspective view thereof, showing the ear cups in a swiveled position.

FIG. 9 is a color, perspective view of a second embodiment of the headphone. The color drawing is necessary to clearly show the presence of colors within the design.

FIG. 10 is a color, front elevational view thereof. The color drawing is necessary to clearly show the presence of colors within the design.

FIG. 11 is a color, rear elevational view thereof. The color drawing is necessary to clearly show the presence of colors within the design.

FIG. 12 is a color, left side elevational view thereof. The color drawing is necessary to clearly show the presence of colors within the design.

FIG. 13 is a color, right side elevational view thereof. The color drawing is necessary to clearly show the presence of colors within the design.

FIG. 14 is a color, top plan view thereof. The color drawing is necessary to clearly show the presence of colors within the design.

FIG. 15 is a color, bottom plan view thereof. The color drawing is necessary to clearly show the presence of colors within the design.

FIG. 16 is a perspective view of a third embodiment of the headphone;

FIG. 17 is a front elevational view thereof;

FIG. 18 is a rear elevational view thereof;

FIG. 19 is a left side elevational view thereof;

FIG. 20 is a right side elevational view thereof;

FIG. 21 is a top plan view thereof; and

FIG. 22 is a bottom plan view thereof.

(Continued)

FIG. 23 is a color, perspective view of a fourth embodiment of the headphone. The color drawing is necessary to clearly show the presence of colors within the design.

FIG. 24 is a color, front elevational view thereof. The color drawing is necessary to clearly show the presence of colors within the design.

FIG. 25 is a color, rear elevational view thereof. The color drawing is necessary to clearly show the presence of colors within the design.

FIG. 26 is a color, left side elevational view thereof. The color drawing is necessary to clearly show the presence of colors within the design.

FIG. 27 is a color, right side elevational view thereof. The color drawing is necessary to clearly show the presence of colors within the design.

FIG. 28 is a color, top plan view thereof. The color drawing is necessary to clearly show the presence of colors within the design.

FIG. 29 is a color, bottom plan view thereof. The color drawing is necessary to clearly show the presence of colors within the design.

FIG. 30 is a perspective view of a fifth embodiment of the headphone;

FIG. 31 is a front elevational view thereof;

FIG. 32 is a rear elevational view thereof;

FIG. 33 is a left side elevational view thereof;

FIG. 34 is a right side elevational view thereof;

FIG. 35 is a top plan view thereof; and,

FIG. 36 is a bottom plan view thereof.

The broken lines are for illustrating portions of the headphone which form no part of the claimed design.

The stippling represents a contrast in appearance as shown.
